UNITED STATES PATENT OFFICE.

LEROY S. TOWNSEND, OF TOLEDO, OHIO, ASSIGNOR OF ONE-HALF TO GEORGE SACO, OF TOLEDO, OHIO.

SCAFFOLD-LIFT.

1,278,792.

Specification of Letters Patent. Patented Sept. 10, 1918.

Application filed July 12, 1918. Serial No. 244,647.

To all whom it may concern:

Be it known that I, LEROY S. TOWNSEND, a citizen of the United States, and a resident of Toledo, in the county of Lucas and 5 State of Ohio, have invented a certain new and useful Scaffold-Lift; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates to lifts, and particularly to a device of this character for use in connection with scaffolds to raise and lower the same.

The object of my invention is the provision of a simple and improved device of the 20 character described, which is capable of being easily and quickly operated to raise a scaffold or to control the lowering thereof and is capable of being locked in any position of adjustment.

25 The invention is fully described in the following specification, and while, in its broader aspect, is capable of embodiment in numerous forms, a preferred embodiment 30 thereof is illustrated in the accompanying drawings, in which,—

Figure 1 is a side elevation of an apparatus embodying the invention.

Fig. 2 is a different elevation thereof with 35 parts in vertical section and with parts removed, and Fig. 3 is a sectional detail of the control portion of the device.

Referring to the drawings, 1, designates 40 a frame, which, in the present instance, is of triangular form with its apex disposed upward, and to the bottom of which frame is centrally secured a sub-frame 2, which extends downward and is intended to be connected in any suitable manner at its lower 45 end to an end of a scaffold to be supported thereby.

A horizontal shaft 3 is mounted in the frame 1 crosswise thereof and fixedly carries a pulley 4, which is preferably circumferentially grooved to provide a run-way 50 for a cable 5 that is intended to extend around the under side of the pulley. This pulley is provided with a plurality of pairs of clutch fingers 6, which are disposed in 55 radial relation to the pulley axis and are

equidistantly spaced circumferentially of the pulley. The clutch fingers of each pair are disposed at opposite sides of the pulley, each being pivoted at its inner end to a respective ear 7 projecting from the side of 60 the pulley, thus adapting the outer ends of the clutch fingers to have swinging movements toward and away from each other. The free ends of the clutch fingers are provided with inward projections or jaws, 8, 65 adapted to oppositely grip a cable extending therebetween on the pulley. The clutch fingers of each set are normally held in spaced or open position by the fingers of a U spring 9 which is mounted in a radial slot or recess 70 10 in the pulley 4 between the fingers.

During a predetermined portion of a revoluble movement of each set of clutch fingers, the lower portion, in the present instance, the outer end portions of the fingers 75 pass between arcuate cam members or bars 11, which coact with the free end portions of the clutch fingers as they pass therebetween to grip an interposed cable to prevent a slipping of the same around the pulley 4. 80 The cam bars 11 are secured at their ends to the frame 1 with the adjacent ends of the bars in flaring relation. The central or intermediate portions of the cam bars are adjustably connected by bolts 12 to facilitate 85 relative transverse adjustment of the bars to suit the desired gripping action of the clutch fingers on the cable. It is preferable to have such a number of clutch fingers and length of the bars 11 that more than one 90 pair of clutch fingers will always be in gripping engagement with a cable on the pulley.

Mounted in the sub-frame 2 below and in parallel relation to the shaft 3 is a shaft 13 which is in driving connection with the shaft 95 3 through a train of gears 14 of suitable ratio. A crank arm 15 is mounted on an end of the shaft 13 for limited rocking movements relative thereto lengthwise of the shaft, being pivoted to the shaft, as at 16, 100 with its hub end provided with an extension 17 at the side of the shaft opposed to the crank arm. A spring, 18, is fixed to the shaft 13 at the inner side of the hub extension 17 and acts on said extension in a manner to exert an outward force thereon and a consequent inward rocking movement to the crank arm. A ratchet wheel 19 is fixed to the sub-frame 2 at the inner side of the crank arm 15 and has its ratchet teeth 20 110

formed on the side thereof in position to coact with the crank arm to prevent a back turning thereof. The crank arm is normally retained in catch engagement with a tooth 5 by the action of a spring 18. When turning the handle 15 its free end is swung out so as not to engage the teeth 20.

The cable 5 is attached at one end to the top or apex portion of the frame 1, thence 10 extends upward over a supporting sheave (not shown) and thence down through a guide 21 on the frame 1 and around the under side of the pulley 4 between the clutch fingers 6. The free end of the cable 5 after 15 leaving the pulley 4 passes over a sheave 22 and thence hangs down free therefrom.

In the use of my apparatus the operator who is mounted on the supported scaffold turns the crank arm 15 to the left when it is 20 desired to take up the cable 5 and elevate the scaffold, and withdraws the crank arm from engagement with the ratchet wheel and permits a turning thereof to the right under the weight of the load when lowering 25 the scaffold. The engagement of cable 5 by the clutch fingers of the pulley, prevents a slipping of the cable with respect to the pulley.

I wish it understood that my invention 30 is not limited to any specific construction arrangement or form of the parts, as it is capable of numerous modifications without departing from the spirit of the claims.

Having thus described my invention, what 35 I claim as new and desire to secure by Letters Patent, is,—

1. In an apparatus of the class described, a frame, a cable clutching pulley mounted in 40 said frame, a cable for supporting said frame and having a portion extending under said

pulley in engagement therewith, means carried by the frame and coöperating with the pulley to cause it to grip the cable, a shaft mounted in said frame and geared to said pulley, a crank arm carried by said shaft, and means for coöperating with said crank arm to prevent a back turning thereof.

2. In an apparatus of the class described, a frame, a pulley mounted in said frame and having a plurality of sets of cable gripping fingers, a cable fixed to said frame and extending upward therefrom over a support and thence down around the under portion of said pulley, cam members carried by said frame at opposite sides of the lower portion of said pulley to coöperate with the cable gripping fingers to cause them to have gripping engagement with the portion of the cable extending under the pulley, a crank journaled in said frame, driving connection between said crank and pulley, and means for coöperating with said crank to prevent a back turning thereof.

3. In an apparatus of the class described, a frame, a pair of shafts journaled in said frame a cable clutch pulley carried by one shaft means carried by the frame for coöperating with the pulley to cause it to grip a cable passing there around, driving connections between said shafts, a crank arm carried by the other of said shafts for limited movements lengthwise thereof, a series of ratchet teeth concentric to said crank shaft, and means acting on said crank to normally retain it in ratchet teeth engaging position.

In testimony whereof I have hereunto signed my name to this specification.

LEROY S. TOWNSEND.
